United States Patent Office.

JONATHAN CRABTREE, OF PHILADELPHIA, PENNSYLVANIA, ASSIGNOR
TO WILLIAM HOGG, JR., OF SAME PLACE.

Design No. 3,838, dated February 8, 1870.

DESIGN FOR A CARPET-PATTERN.

The Schedule referred to in those Letters Patent and making part of the same.

I, JONATHAN CRABTREE, of Philadelphia, county of Philadelphia, State of Pennsylvania, have invented a Design for a Carpet-Pattern, of which the following is a specification.

The figure in the accompanying drawing represents sufficient of a carpet pattern to illustrate my design, the remainder being only a repetition of that which appears.

The design, taken as a whole, consists of the members or figures A and B, of curved bars or ribs C and C', emerging from these figures and crossing each other, and of a wreath, D, which is entwined about the said bars at the point of their intersection.

The complete figure, A, consists of a square or diamond-shaped centre-piece, *a*, around which is arranged a row of single leaves, *b*; these leaves being in turn surrounded by a second row of leaves, *c*, of a character differing from the former, and which constitute the outer border of the figure.

The figure B, when completed, is also square, or nearly so, and consists of waved lines, scrolls, and bunches of fruit, intermingled and arranged in a man-

ner too clearly shown in the drawing to need description.

The curved rib C has, in the centre, a longitudinal foliated ornament, *f*, and the bar C' is ornamented by a series of curved and angular lines and central spots, *h*, as shown.

The wreath D consists of flowers, leaves, and stems, arranged substantially as represented.

A number of minute spots is arranged regularly upon the ground-work of the pattern.

Irrespective of the colors employed,

I claim—

The design for a carpet-pattern, substantially as described and as represented in and by the accompanying drawing.

In testimony whereof, I have signed my name to this specification in the presence of two subscribing witnesses.

JONATHAN CRABTREE.
